LADY'S STOCKING

Frank Hoffecker, Charlotte, N. C., assignor to Chadbourn Hosiery Mills, Inc., Charlotte, N. C., a corporation of North Carolina

Application August 25, 1952, Serial No. 21,182

Term of patent 14 years

(Cl. D47—7)

To all whom it may concern:

Be it known that I, Frank Hoffecker, a citizen of the United States, residing at Charlotte, in the county of Mecklenburg and State of North Carolina, have invented a new, original, and ornamental Design for a Lady's Stocking, of which the following is a specification, reference being had to the accompanying drawing forming part thereof, in which:

Fig. 1 is a side elevational view of a lady's stocking, showing my new design; and

Fig. 2 is a fragmentary rear perspective view of the stocking shown in Fig. 1.

I claim:

The ornamental design for a lady's stocking, as shown.

FRANK HOFFECKER.
